United States Patent Office

Des. 186,514
Patented Nov. 3, 1959

186,514

TROPHY BASE

Nicholas F. Tangney, New York, N.Y.

Application August 11, 1958, Serial No. 52,166

Term of patent 3½ years

(Cl. D29—23)

FIG. 1

FIG. 3

FIG. 2

Figure 1 is a front perspective view of a trophy base, showing my new design;

Figure 2 is a reduced front elevational view; and
Figure 3 is a reduced top plan view thereof.

The dominant features of my design reside in the portion shown in full lines.

I claim:

The ornamental design for a trophy base, substantially as shown, and described.
